UNITED STATES PATENT OFFICE.

ARTHUR M. SHEAKLEY, OF STOCKTON, CALIFORNIA, ASSIGNOR TO HERCULES MANUFACTURING COMPANY, OF STOCKTON, CALIFORNIA, A CORPORATION.

FIBER-CUTTING MACHINE.

No. 806,753.

Specification of Letters Patent.

Patented Dec. 5, 1905.

Application filed August 30, 1904. Serial No. 222,768.

To all whom it may concern:

Be it known that I, ARTHUR M. SHEAKLEY, a citizen of the United States, residing at Stockton, in the county of San Joaquin and State of California, have invented certain new and useful Improvements in Fiber-Cutting Machines; and I do declare the following to be a full, clear, and exact description of the invention, such as will enable others skilled in the art to which it appertains to make and use the same, reference being had to the accompanying drawings, and the figures of reference marked thereon, which form a part of this specification.

My invention relates to improvements in machines used in cutting Manila fiber or old Manila rope into suitable lengths to be prepared for use in making mortar for plastering purposes and the like; and it consists in the peculiar and effective construction and relative arrangements of parts herein specified.

My object is to produce a machine which will quickly and effectually cut the fiber into suitable lengths and convey the same to a suitable picking or other machine, and I accomplish said object by the construction herein-after fully described, and particularly pointed out in the claims appended.

Referring now to the drawings, Figure 1 represents a top plan view of my improved machine. Fig. 2 is a sectional view of a feeder and cutter. Fig. 3 is a side elevation of a shaft-box carrier. Fig. 4 is a side elevation of a shaft-box. Fig. 5 is an end elevation of same. Fig. 6 is a front elevation of a cutter-blade. Fig. 7 is a side elevation of a cutter-wheel. Fig. 8 is a sectional view of a shaft-box holder. Fig. 9 is a side elevation of my improved fiber-cutting machine. Fig. 10 is a sectional view of a feed-roller. Fig. 11 is a longitudinal sectional view, on a reduced scale, of the conveyer and conveyer-box.

Similar numerals of reference indicate corresponding parts in the several views.

On suitable upright supporting-beams 1 are fastened beams 2 and 2^a. Across the upper sides of said beams 2 and 2^a are fastened beams 3, 4, 4^a, 5, 6, 7, and 8 at any desired points. On the beams 3 and 4 and 4^a is fastened an iron plate 9, which plate is provided with a slot 10, said slot having an upwardly-projecting rim 11. Over one end of said slot is a dust-flue 12, as shown in section in Fig. 1. A shaft 13 is mounted on said plate 9 and extends across the slot 10 at the center thereof.

On said shaft is rigidly attached a cutter-wheel 14, provided with arms 15, which wheel rotates in the slot 10. On each of said arms are two outwardly-projecting lugs 16, forming component parts of said arms. On said lugs knives 17 are bolted or otherwise fastened, said knives extending downward from said lugs. Said lugs are a sufficient distance apart and extend a considerable distance from the arms 15, thus leaving a space 18 between the knives and the arms. Beneath each lug 16 set-screws 19 extend through the arms 15 and into the knives 17 and are adapted to be used to adjust the position of said knives.

20 is a feed-box resting on the beams 5, 6, and 7, which feed-box has a narrow portion 70 21, which opens into the slot 10 just in front of the shaft 13.

The shaft 13 extends across the beam 5 and is seated in a bearing 22 on the beam 6. At the end of said shaft which extends over the beam 6 is a clutch mechanism 23, operated by means of a lever 23^a, at the end of which clutch mechanism is a bevel-gear 24, intermeshing with two bevel-gears 25 and 26, attached to shafts 27 and 28, respectively, which shafts are journaled on the beam 7. On the shaft 28 is a sprocket-wheel 29, on which is a linked belt 30, connecting it to a larger sprocket-wheel 31, which wheel is on a shaft 32, journaled on the under sides of the beams 85 2^a. On one end of the shaft 32 is a small sprocket-wheel 33. A link belt 34 connects the sprocket-wheel 33 to a sprocket-wheel 36, located on the end of a shaft 37, which shaft is journaled on the plate 9. On the shaft 37 90 is suitably arranged a roller 38, said roller being located in an iron block 47, secured on the plate 9 just under the part 21, said roller extending upward to a level with the floor of the feed-box 20. On the end of the shaft 27 95 is a sprocket-wheel 39. A link belt 40 connects said sprocket-wheel 39 to a sprocket-wheel 41, fastened on a shaft 42, which shaft is journaled on the plate 9. On said shaft is a corrugated roller 43, which roller fits between the sides of the narrow portion 21 of the feed-box 20 just over the roller 38. Said roller is square-seated on the shaft 42, said square portion in the roller being tapered from the ends to the center, as shown in Fig. 105 10. On the side of the roller 43 which is farthest from the sprocket-wheel 41 the shaft 42 is seated in a box 44 having guide-arms 45,

which box fits between two arms 46, forming component parts of a base-plate 47^a, which base-plate forms a component part of the block 47. Said arms curve slightly toward 5 the roller 43. On the free end of said shaft 42 a weight 43^a is suspended from said shaft by means of a rope 49. Near the sprocket-wheel 41 the shaft 42 is seated in a box 50, which box is pivotally mounted between the 10 jaws 51 of a Y-shaped standard 52.

A plate 53 is fastened onto the beam 4 and extends upward in front of the roller 43, in which plate is a feed-opening directly in front of the roller 43. A cast-iron plate 54 is bolted 15 or otherwise fastened onto the plate 53 and has a similar coinciding feed-opening. On the plate 54 is welded a steel cutting-blade 55, which cutting-blade has a similar coinciding feed-opening, as has the plate 54. This blade 55 20 is so arranged as to coact with the knives 17 as the wheel 14 revolves.

Under the slot 10 is a conveyer-box 56, open at one end and closed at the other. Near the open end are secured two shafts 58 and 58^a, 25 arranged one above the other, and near the closed end is secured a shaft 57, on which shaft are secured sprocket-wheels 59. On the shaft 58 are secured sprocket-wheels 60, and on the shaft 58^a are secured smooth pulleys 30 60^a. Link belts 61 operatively connect said sprocket-wheels and pulleys. On said link belts are rigidly attached slats 62, which drag on the floor of the conveyer-box 56. On the shaft 58 outside the box 56 is fastened a pulley 63, on which is a belt 64, connecting said pulley to a similar pulley 65 on a shaft 66, which shaft is journaled on the beams 5 and 6; on the other end of which shaft is a bevel-gear 67, which intermeshes with a bevel-gear 40 68, which last-named gear is rigidly attached onto the shaft 27.

The operation is as follows: Any suitable motive power is applied to the shaft 13, which revolves the wheel 14. The clutch device 23 45 is thrown together by means of the lever 23^a, as is apparent. This starts in motion the feed-rollers 43 and 38 and also the conveying apparatus in the conveyer-box 56. The rope or other material is then fed between the 50 rollers 43 and 58 and is cut into the desired lengths by means of the knives 17 and the cutter-blade 55, and then it falls onto the conveyer below said wheel and is conveyed to any point desired. The shaft 42, being 55 pivotally mounted, allows large or small ropes to pass beneath the roller 43, and said roller, being pivotally mounted, as shown in Fig. 10, always stays in a position relative to the size of the material passing under it. 60 The space 18 allows the cut material to fall down onto the conveyer and not choke up around the knives. The dust-chute 12 is to convey dust, &c., to outside of the building.

The set-screws 19 are for the purpose of 65 adjusting the knives 17 and keeping them so

that they will always pass in close contact with the blade 55. This construction is particularly advantageous in view of the fact that the knives are not always true when made and are inclined to bend one way or the 70 other; but by use of the set-screw they may be adjusted to the required position.

The purpose of having a slight curve in the standards 46 is to prevent the box 44 from binding as it moves up or down between said 75 standards.

The advantage of having two shafts at the open end of the conveyer 56 is to permit the slats 62 to travel vertically for a short distance, thus allowing all material thereon to 80 drop off and not carry it back into the conveyer again. A suitable box or other covering may be placed over the wheel 14 when the same is in motion, thus preventing it from throwing any of the cut material outside of 85 the machine.

Many changes may be made in my invention without departing from the spirit thereof. Hence I consider myself entitled to all forms of the invention as fairly fall within 90 the scope of my claims.

Having thus described my invention, what I claim as new and useful, and desire to secure by Letters Patent, is—

1. In a device of the kind described the combination of upright beams and cross-beams thereon, a slotted plate arranged on said cross-beams, a shaft journaled on said plate and extending across the middle of said slot, a wheel secured on said shaft and working in 100 said slot, cutting-knives secured on the arms of said wheel, and a suitable feed device opening into said slot, at a point where the said knives pass, as described.

2. In a device of the kind described the combination of upright beams and cross-beams thereon, a plate provided with a longitudinal slot arranged on said cross-beams, a shaft journaled on said plate and extending across the middle of said slot, a wheel secured on 110 said shaft and working in said slot, two outwardly-projecting lugs secured on each arm of said wheel, knives secured on the ends of said lugs, and a feed device opening into said slot at a suitable point, as described.

3. In a device of the kind described the combination of upright beams and cross-beams thereon, a slotted plate arranged on said cross-beams, an upwardly-projecting rim around 120 said slots, a shaft journaled on said plate and extending across the middle of said slot, a wheel secured on said shaft and working in said slot, two outwardly-projecting lugs secured on each arm of said wheel, knives secured on the ends of said lugs, set-screws in 125 said knives and extending through said arms, and a feed device opening into said slot at a suitable point, as described.

4. In a device of the kind described the combination of upright beams and cross-beams 130

thereon, a slotted plate arranged on said cross-beams, a cutting device arranged and working in said slot, a feed device opening into said slot, said feed device consisting of two rollers one above the other, and means for rotating said rollers both in the same direction as specified.

5. In a device of the kind described the combination of upright beams and cross-beams thereon, a slotted plate arranged on said cross-beams, a cutting device arranged and working in said slot, a feed device leading to said cutting device, said feed device consisting of two rollers one arranged above the other, the 10 upper roller being corrugated, said upper roller being pivotally mounted on a suitable shaft journaled on said plate, and means for rotating said rollers both in the same direction, as specified.

15 6. In a device of the character described, the combination of upright beams and cross-beams thereon, a slotted plate arranged on said cross-beams, a cutting device arranged and working in said slot, a feed device leading 20 to said cutting device and composed of two rollers one arranged above the other, the upper roller being pivotally mounted on a suitable shaft said shaft being pivotally journaled on said plate, and means for rotating said rollers both in the same direction, as specified.

25 7. In a cutting-machine a feed device consisting of two shafts journaled one above the other at suitable points on said machine, said upper shaft being pivotally journaled between the two upright jaws of a Y-shaped standard, a roller on each shaft arranged one above the other, said upper roller being corrugated and pivotally mounted on its shaft, two standards suitably arranged on the body of the machine 30 at one end of said upper roller and curving slightly toward said roller, a shaft-box suitably arranged between said standard in which box is seated the said upper shaft, means for rotating said shafts and a suitable cutting device arranged in front of said feed device, as specified.

35 8. In a device of the kind described the combination of upright beams and cross-beams arranged thereon, a slotted plate arranged on said cross-beams, a shaft journaled on said plate and extending across the middle of said slot, a wheel secured on said shaft and acting in said slot, a cutting device arranged on said wheel, a feed device leading to said cutting device, a conveyer arranged below said wheel and composed of a box opened at one end and closed at the other, two shafts arranged near the open end one above the other, smooth pulleys secured on the lower 40 shaft and sprocket-wheels on the upper, a shaft arranged near the closed end of said box, chains connecting said sprocket-wheels and pulleys, slats arranged on said chains, and means for rotating said shafts, as specified.

45 9. In a device of the kind described, the com-

bination of upright beams and cross-beams thereon, a slotted plate arranged on said cross-beams, an upwardly-projecting rim around said slot, a shaft journaled on said plate and extending across the middle of said slot, a 70 wheel secured on said shaft and working in said slot, cutting-knives suitably arranged on said wheel, a feed device leading to said slot, the plate 53 secured in front of said feed device, the plate 54 attached to said plate 53, and 75 the cutter-blade 55 welded to said plate 54 and adapted to coact with the said knives, as set forth.

10. In a device of the kind described the combination of upright beams, the longitudinal beams 2 and 2^a secured on said upright beams, the cross-beams 3, 4, 4^a, 5, 6, 7 and 8 secured across said longitudinal beams, a slotted plate secured on the beams 3, 4^a, and 4, an upwardly-projecting rim around said slot, the 80 shaft 13 journaled on said plate and on said beam 6 said shaft extending across the middle of said slot, a wheel secured on said shaft and working in said slot, two lugs on each arm of said wheel, a knife secured on the ends of each 85 pair of said lugs, a set-screw secured in each of said knives and extending through said arms, the shafts 27 and 28 journaled on the beam 7 and connected to the shaft 13 by suitable beveled gears, a clutch device on the shaft 90 13 adapted to throw said shaft in or out of connection with said shafts 27 and 28, the shaft 37 journaled on the said plate, the smooth roller 38 secured on said shaft, means for connecting said shaft with the shaft 37, the shaft 100 42 pivotally journaled near one end on the said plate and extending over said shaft 37, a weight on the other end of said shaft, the corrugated roller 43 pivotally mounted on said shaft 42 just above the roller 38, two standards secured 105 on the said plate at one end of said roller 43 and curving slightly toward said roller, a shaft-box adjustably secured between said standards in which shaft-box is seated the shaft 42, means for connecting said shaft 42 to said shaft 27, 110 a conveyer arranged beneath the said wheel and operatively connected with the shaft 28 by suitable means, and a feed-box 21 secured on the beams 5, 6, 7 and 8 and leading to the roller 38 and 43, as specified.

11. In a fiber-cutting machine, the combination with the cutter-wheel, cutter-knives carried thereby, and the drive-shaft on which the wheel is mounted, of a cutting-blade coacting with the cutter-knives, and having a feed-opening, feed-rollers disposed one above the other to receive and feed the fiber to the cutter-knives and cutting-blades, the upper of said rollers being corrugated, and being mounted on its shaft to have rocking movement thereon to accommodate different thicknesses of fiber, a conveyer-box arranged to receive the cut fiber from the knives, an endless conveyer traveling in said box to discharge the cut fiber therefrom, and means for operating the feed- 125 130

rollers and endless conveyer from the drive-shaft.

12. In a fiber-cutting machine, a wheel, knives carried by said wheel, a stationary cutting-blade having its sides disposed in planes parallel to the planes described by the cutting edges of said knives.

In testimony whereof I have signed my name to this specification in the presence of two subscribing witnesses.

ARTHUR M. SHEAKLEY.
